UNITED STATES PATENT OFFICE.

ERNST RIED, OF MUNICH, BAVARIA, GERMANY.

FLAG-STAFF HOLDER.

SPECIFICATION forming part of Letters Patent No. 415,220, dated November 19, 1889.

Application filed July 15, 1889. Serial No. 317,547. (No model.)

To all whom it may concern:

Be it known that I, ERNST RIED, of Munich, Bavaria, Germany, have invented an Improved Flag-Staff Holder, of which the following is a specification.

This invention relates to an adjustable flag-staff holder that may be secured to windows without injuring them.

It consists in the various features of improvement, more fully pointed out in the claim.

In the accompanying drawings, Figure I is a vertical longitudinal section of my improved flag-staff holder. Fig. II is an end view, and Fig. III a top view, thereof.

The letters *a b* represent two superposed plates slotted lengthwise and clamped together by bolts *h* and winged nuts *h'*. The bolts pass through the slots, and by loosening the winged nuts the plates *a b* may be drawn apart to any desired extent. To one end of plate *a* there is connected a fork *c*, having the arms *c'*. To the opposite end of plate *b* there is connected a similar fork *d*, having

the arms *d'*. These arms have hook-shaped ends, so that the flag-staff A may be secured within the forks by strings *i*, slipped over the hooks. To the fork *c* there is hinged a leaf *e*, and to the fork *d* there is hinged a U-shaped plate *f*.

In use the holder is set to the required length and the leaf *e* is secured by hood *g* to the wall, while the plate *f* is caused to engage the window-sill.

What I claim is—

The combination of a pair of adjustable plates with clamping-bolts engaging the plates, a pair of forks secured to the plates for supporting a flag-staff, and with a pair of fastening-leaves for securing the plates to a wall, substantially as specified.

In testimony whereof I have signed this specification in the presence of two subscribing witnesses.

ERNST RIED.
